UNITED STATES PATENT OFFICE.

JOHN DOUGLAS, OF NEWARK, NEW JERSEY, ASSIGNOR TO THE SINGER MANUFACTURING COMPANY, A CORPORATION OF NEW JERSEY.

MULTIPLE-TUCK FOLDER FOR SEWING-MACHINES.

1,024,317.

Specification of Letters Patent. Patented Apr. 23, 1912.

Application filed February 12, 1908, Serial No. 415,561. Renewed August 28, 1911. Serial No. 646,544.

To all whom it may concern:

Be it known that I, JOHN DOUGLAS, a citizen of the United States, residing at Newark, in the county of Essex and State 5 of New Jersey, have invented certain new and useful Improvements in Multiple-Tuck Folders for Sewing-Machines, of which the following is a specification, reference being had therein to the accompanying drawings.

This invention has for its object to provide a multiple tucking device for sewing machines in which the parallel tucks are of greater depth than their spacing apart, 15 whereby the outer edge of each tuck is caused to overlie and conceal the line of stitching at the base of an adjacent tuck.

The invention consists in the construction and arrangement of parts herein shown and 20 described and set forth in the claims.

The present improvement is shown herein embodied in that class of multiple tuck-folding attachments forming the subject of the United States patent to C. H. Foster No. 25 575,342, dated January 19, 1897.

In the accompanying drawings, Figure 1 is a perspective view, and Fig. 2 a front end view of the forward portion of a sewing machine provided with the present improvements, and Fig. 3 a plan view of the same with the bracket-arm omitted. Fig. 4 is an 30 edge view of the lower tuck-forming member, and Fig. 5 a transverse section thereof on the line $\alpha\alpha$ of Fig. 3. Fig. 6 is a perspective view of one of the fold-turning blades, and Fig. 7 a similar view, taken from the under side of the presser-foot constituting one of the operative members of the attachment. Fig. 8 is a bottom view of a 35 portion of the presser-foot and Fig. 9 is a perspective view of a section of fabric provided with a series of tucks produced by the attachment.

To the forward portion of the bed-plate 45 1 is secured by means of fastening screws 2 the lower fluted plate 3 of the attachment which affords a series of convergent tapering ribs 5 with intermediate grooves 4 beginning in the nearly flat front or receiving 50 edge of the plate and increasing in depth and decreasing in width toward the delivery end, the ribs 5 adjacent the delivery end merging into the flat folding blades or tongues 5 $\times$ which in their advance to the 55 delivery end of an extension 3 $\times$ of the plate

3 to the throat-plate are gradually turned over into an acute angle with the surface of said plate. The upper forming member consists of a similar plate 6 correspondingly fluted upon its under face to fit the flutes of the forming plate 3, and is thus provided with a spaced series of convergent grooves 7 loosely fitting the ribs 5 of the plate 3. As will be observed, the ribs and grooves are so shallow and are formed with such gradual curves in their receiving ends as to produce slightly sinuous lines at the forward edges of the folding plates between which the material may be introduced in substantially flat condition, so as to present no 60 abrupt angles to obstruct the work in its passage to the stitching mechanism. The delivery end of the forming plate 6 is cut away at the top to expose the upper portions of the ribs 5 adjacent their junction with the portions 5 $\times$ to insure against the obstruction of the free passage of the material over such ribs around the bends therein, and also for access by a suitable instrument in introducing the material preparatory to a tuck-stitching operation. The plate 6 is further provided with an elongated inspection aperture 8 through which the goods may be 65 inspected and through which it may be assisted over the forming ribs 5 in its introduction into the attachment.

As in the patent above mentioned, the upper tuck-folding plate 6 is carried by a bracket-piece secured thereto by means of fastening screws 9 and having parallel upwardly extending guide-arms 10 provided with the vertical slots 11 entered by screw-studs 12 projecting from the laterally channeled guide-block 13 formed at the outer end of a supporting bar 14 which is secured 90 by means of a screw 15 to the lower end of the head of the sewing machine bracket-arm 16. The upper portions of the guide-arms 10 are pivotally connected by means of screws 17 to the lower ends of the links 100 18 whose upper ends are pivotally connected by means of screws 19 with lifting crank-arms 20 fixed upon the opposite ends of the rock-shaft 21 journaled in bearing lugs 22 of the guide-block 13 intermediate which is 105 fixed thereon the lifting lever 23 by which the upper tuck-forming plate 6 may be raised and lowered for introduction and engagement of the material.

The supporting bar 14 is notched inter- 110

mediate its ends to receive the vertical arm 24 of the carrier-bar 25 attached thereto by means of the fastening screw 26. The carrier-bar 25 is provided with a series of vertical sockets in which are secured by means of screws 27 the cylindrical shanks 28 of the fold-turning blades 29, each of which has its upper or body portion shaped correspondingly with the operative face of one of the 10 folding tongues 5^x and has at its lower edge a flange 30, each of such fold-turning blades being sustained adjacent the upper side of the inclined tongue 5^x with its lower flange 30 slightly spaced from the top of the folding plate extension 3^x intermediate the bases of the adjacent tongues 5^x. The presser-foot 31 is provided, as is usual in multiple-needle chain-stitch machines, with a series of elongated needle-holes 32 to receive the needles 20 33 carried by the multiple needle-clamp 34 mounted upon the needle-bar 35 of the machine, and adjacent each needle-hole, upon the side opposite that in which the tuck-forming tongues 5^x are inclined, is formed 25 a curved slot 36 extending from a point at the front end of the presser-foot in advance of the needle-hole to a point rearward of said needle-hole. To insure the proper guidance of the tucks formed in the material and 30 delivered from the forming tongues 5^x, the front portion of each guide-slot 36 is formed upon the edge 37 in advance of the needle with an inclination in the same direction as that of the adjacent tongue 5^x the side walls 35 of the slot are so arranged, and particularly that nearest the needle-hole, that while the forward portion conforms with the inclination of the adjacent end of the fold turning blades, the middle portion, or that closest 40 to the needle-hole, is substantially parallel with the latter or with the needle-path so as to turn the tucks upward parallel with the needle adjacent the stitching point, while the rearward portion of the slot behind the 45 needle is inclined in the same direction as the fold turning blades, and the ends of the slot are undercut so as to gradually turn downwardly the outer edges of the tucks to be pressed down upon the body of the goods 50 by the continuous heel portion extending across the foot rearward of the tuck-guiding spaces afforded by the slots 36. As will be seen by reference to the drawings, the tuck-guiding or deflecting slots 36 are arranged 55 closer to their respective needle-holes than to the adjacent needle-holes, so that the bodies of the several overlying tucks are pressed downwardly upon the body fabric by the presser-foot, and only the outer portion or crown of each tuck is deflected upwardly out of the path of the needle which secures the adjacent tuck in position. By 60 this means, the greater portion of the tuck is introduced beneath the presser-foot in the 65 position in which it is finally delivered from

the machine, and only the tip of the tuck diverted to be subsequently ironed down to the body fabric after passage of the stitch-forming mechanism, which insures the delivery of the work smoothly from beneath the presser-foot and without the wrinkling or crimping which the tucks would receive if delivered to the stitch-forming mechanism in standing position to be ultimately flattened out by the action of that portion of the 70 presser-foot rearward of the needle-apertures. 75

As shown herein, the throat-plate 39 is provided with the usual feed-dog apertures 40 and with needle-holes 41 each disposed in front of but nearly in line with the edge of the flange 30 of each fold-turning blade 29, whereby a line of stitching may be produced through the body of the fabric and the base portion of each tuck overlying the 80 85 same.

In the operation of the attachment, the upper folding plate 6 is raised and a piece of material *m* introduced into the same over the lower folding plate 3 and intermediate 90 the tongues 5^x and fold-turning blades 29, with the outer portions of the folds *m*^x thus produced entering their respective guide-slots 36 of the presser-foot. The upper folding plate 6 is then lowered and the machine 95 started, when the operation of the feed acts in the ordinary manner to draw the material through the convergent intermeshing tuck forming ribs and grooves into a series of parallel standing tucks which are led over 100 the tongues 5^x and under the fold turning blades 29 with their body portions beneath the flat lower face of the presser-foot 31, but with their outer portions deflected upwardly out of the needle-paths through the 105 guide-slots 36, whereby parallel seams *s* are produced through the body of the fabric *m* and the bases of the tucks *m*^x, as represented in Fig. 9.

By reference to Fig. 7, it will be observed 110 that the inner end of each of the slots 36 has a bevel substantially the same as that of the forward portions of the presser-foot intermediate the slots, so that, as the outer marginal portions of the tucks enter the 115 rearward portions of the guide-slots they are turned downwardly and are finally pressed flat upon the bases of the adjacent folds by the continuous heel portion of the presser-foot, of which the shank is composed of two parts pivotally connected together by means of the screw-pin 39, as represented in Figs. 1 and 2, to enable it to accommodate itself to the work.

As will be observed, the curved body portions 29 of the fold-turning blades coöperate 120 with the tongues 5^x in turning over the tucks formed upon the ribs 5 so as to overlie the intermediate body portion of the fabric, while the flanges 30 serve to maintain such 130

intermediate body portion flat intermediate the bases of the tucks to insure proper delivery beneath the presser-foot for the action of the stitch-forming mechanism.

5 While I have herein shown a preferred embodiment of the present improvement, it is to be understood that the present invention embraces other forms and arrangements of parts for producing the described 10 result in a substantially similar manner, and that the present invention is not therefore limited to the particular embodiment herein shown and described.

From the foregoing description, it will 15 be seen that the present invention is directed to a means for producing simultaneously a plurality of tucks, that is, two or more, of which at least one has a greater width than its spacing from the adjacent tuck 20 whose base it overlies, and the number and relation of any other tucks which the apparatus is designed to produce simultaneously therewith is not material. As the present improvement is not directed to any 25 specific form or construction of upper and lower tuck-forming members, which are designated flutes for convenience in the foregoing description, it is evidently unessential that these members be constructed as 30 specifically shown and described herein.

Having thus set forth the nature of the invention, what I claim herein is:—

1. The combination with a sewing machine provided with stitch-forming mechanism comprising a plurality of reciprocating needles, of a multiple tuck-folding attachment comprising means for producing a plurality of spaced parallel tucks overlying the body of the fabric and of greater 40 width than their spacing apart, and a presser-foot provided with a plurality of needle-holes and a plurality of curved guide-slots each embracing a needle-hole upon one side and formed with side walls 45 correspondingly inclined forwardly and rearwardly of the needle-hole.

2. A multiple tuck-folding attachment for sewing machines comprising upper and lower fluted plates having a plurality of rearwardly converging intermeshing ribs and grooves extending substantially in the direction of feed of the work of a depth at their delivery ends greater than their spacing apart, said ribs merging at their delivery ends into laterally inclined tongues and presenting at their receiving ends slightly sinuous lines to facilitate the introduction of the material between the forward edges of the plate in substantially 50 flat condition, a plurality of fold-turning blades having their body portions overlying said inclined tongues and provided with flanges extending intermediate the bases of said tongues, and a presser-foot having a 55 heel portion with continuous work-engaging

face extending across the same and formed with a series of forwardly projecting fingers each provided with a needle-hole and affording intermediate tuck-guiding spaces in alignment with the forward extremities of 70 said blades, the sides of said fingers being inclined rearward of the needle-holes to lay the tucks flat for engagement of the heel portion of the presser-foot after the stitching operation, whereby the tucks are delivered in flat condition. 75

3. A multiple tuck-folding attachment for sewing machines, comprising upper and lower fluted plates having a plurality of rearwardly converging intermeshing ribs 80 and grooves extending substantially in the direction of feed of the work and of a depth at the delivery ends greater than their spacing apart, said ribs extending in advance of the upper plate and merging into laterally 85 inclined tongues, a plurality of fold-turning blades having their body portions overlying said inclined tongues and provided with flanges extending intermediate the bases of 90 said tongues, and means in alignment with the delivery ends of said tongues for deflecting the folds delivered by said tongues laterally in the opposite direction from their inclination to expose the bases of the adjacent tucks for stitching. 95

4. The combination with a multiple needle sewing machine adapted for stitching simultaneously a plurality of parallel seams, of a multiple tuck-folding attachment comprising means for producing a plurality of spaced parallel tucks of greater width than their spacing apart and including a plurality of laterally inclined tongues over which the tucks are delivered, and a plurality of fold-turning blades having inclined portions overlying said tongues for causing said tucks to be delivered to the stitch-forming mechanism with their bases overlying the body of the fabric, and a presser-foot provided with a plurality of 100 needle-holes and a corresponding number of guide-slots each extending from the front of said foot in advance of one of said needle-holes laterally in the opposite direction from that of the inclination of said tongues, said 105 guide slots having their side walls substantially parallel with the needle holes adjacent the latter and being inclined similarly to the fold-turning blades forwardly and rearwardly thereof, whereby the outer edges 110 of the tucks are deflected out of the path of the needles entering said needle-holes in the presser-foot. 115

5. The combination with a multiple needle sewing machine adapted for stitching simultaneously a plurality of parallel seams, of a multiple tuck-folding attachment comprising means for producing a plurality of spaced parallel tucks of greater width than their spacing apart and in- 120 125 130

cluding a plurality of laterally inclined tongues over which the tucks are delivered, and a plurality of fold-turning blades having inclined portions overlying said tongues 5 for causing said tucks to be delivered to the stitch-forming mechanism with their bases overlying the body of the fabric, and a presser-foot provided with a plurality of needle-holes and a corresponding number 10 of curved guide-slots each extending from the front of said foot in advance of one of said needle-holes to a point behind the same and embracing the latter upon the side opposite the direction of inclination of said 15 tongues, whereby the outer portions of the tucks are laterally deflected to expose the bases of the adjacent tucks for passage of the needles and are thereafter restored to initial relation with the bodies of the tucks 20 to conceal the stitching upon the bases thereof.

6. The combination with a multiple-needle sewing machine adapted for stitching simultaneously a plurality of parallel 25 seams, of a multiple tuck-folding attachment comprising means for producing a plurality of spaced parallel tucks of which at least one has a greater width than its spacing from the adjacent tuck to enable 30 it to overlie the base of the latter, and a plurality of tuck-guides for directing said tucks to the stitch-forming mechanism with their bases overlying the body of the fabric, and a presser-foot provided with a plurality 35 of needle-holes and a guide-slot embracing each needle-hole corresponding with the tuck whose base is overlaid by the adjacent tuck, said guide-slot being bowed laterally from the front of the foot in advance of 40 the needle-hole to a point rearward of the needle-hole and formed with unbroken opposite walls, whereby the outer edge of the overlying tuck is deflected out of the path of the needle entering said needle-hole.

45 7. The combination with a multiple-

needle sewing machine adapted for stitching simultaneously a plurality of parallel seams, of a multiple tuck-folding attachment comprising means for producing a plurality of spaced parallel tucks of which 50 at least one has a greater width than its spacing from the adjacent tuck to enable it to overlie the base of the latter, and a plurality of tuck-guides for directing said tucks to the stitch-forming mechanism with their 55 bases overlying the body of the fabric, and a presser-foot provided with a plurality of needle-holes and a guide-slot embracing each needle-hole corresponding with the tuck whose base is overlaid by the adjacent tuck, 60 said guide-slot being bowed laterally from the front of the foot in advance of the needle-hole to a point rearward of the needle-hole and disposed nearer to its respective needle-hole than to the adjacent 65 needle-hole.

8. A multiple tuck-folding attachment for sewing machines comprising upper and lower spaced and convergent intermeshing tuck-folding members with laterally inclined tongues constituting continuations of the lower folding members, tuck-guides formed with flanges extending beneath said tongues and intermediate their bases, and a presser-foot provided with a plurality of 70 needle-holes and a plurality of guide-slots each extending from the front of said foot in advance of one of said needle-holes laterally in the opposite direction from that of the inclination of said tongues, said guide-slots having their side walls inclined 75 reversely from said tongues forwardly and rearwardly of the needle.

In testimony whereof, I have signed my name to this specification, in the presence 85 of two subscribing witnesses.

JOHN DOUGLAS.
